US0D1084025S

(12) **United States Design Patent** (10) Patent No.: **US D1,084,025 S**
Knatt (45) Date of Patent: ** Jul. 15, 2025

(54) **DISPLAY SCREEN OR PORTION THEREOF INCLUDING ICONS**

(71) Applicant: **True Manufacturing Co., Inc.**, O'Fallon, MO (US)

(72) Inventor: **Kevin D. Knatt**, St. Louis, MO (US)

(73) Assignee: **True Manufacturing Co., Inc.**, O'Fallon, MO (US)

(**) Term: **15 Years**

(21) Appl. No.: **29/873,274**

(22) Filed: **Mar. 29, 2023**

(51) LOC (15) Cl. **14-04**

(52) U.S. Cl.

USPC **D14/492**

(58) **Field of Classification Search**

USPC D14/485-495

See application file for complete search history.

Primary Examiner — Rachel A. Voorhies

Assistant Examiner — Gary N Chamberlin

(74) Attorney, Agent, or Firm — Stinson LLP

CLAIM

The ornamental design for the display screen or portion thereof including icons, as shown and described.

DESCRIPTION

The sole FIGURE is a face view of a display screen or portion thereof including icons.

Broken lines in an equal length dash pattern form no part of the claimed design.

Broken lines in a long-long-short dash pattern indicate an unclaimed boundary line between a display screen and an unclaimed bezel of a display device including the display screen.

1 Claim, 1 Drawing Sheet
